COMBINED HOLD DOWN CLAMP AND BASE SUPPORT FOR BATTERIES**Jacob J. Delzer, 3212 Fruitvale Blvd.,
Yakima, Wash. 98902****Filed Feb. 25, 1970, Ser. No. 21,614****Term of patent 14 years****Int. Cl. D13—02****U.S. Cl. D26—6****FIG. 1****FIG. 2**

FIG. 1 is a left front perspective view of a combined hold down clamp and base support for batteries embodying my new design with the latch in a locked position; and

FIG. 2 is a right rear perspective view with the latch in an unlocked position.

The broken lines shown in FIGS. 1 and 2 are for illustrative purposes only.

I claim:

The ornamental design for a combined hold down clamp and base support for batteries, substantially as shown and described.
